UNITED STATES PATENT OFFICE.

JOHN F. TOOMEY, OF NEW YORK, N. Y., ASSIGNOR TO AMERICAN TELEPHONE AND TELEGRAPH COMPANY, A CORPORATION OF NEW YORK.

REPEATER CIRCUIT.

1,407,604.

Specification of Letters Patent. Patented Feb. 21, 1922.

Application filed October 16, 1917. Serial No. 196,896.

To all whom it may concern:

Be it known that I, JOHN F. TOOMEY, residing at 111 W. 84th Street, New York city, in the county of New York and State of 5 New York, have invented certain Improvements in Repeater Circuits, of which the following is a specification.

This invention relates to telephone repeaters and more particularly to repeater organizations employing repeater elements of 10 the so-called mechanical type.

One of the objects of the invention has reference to the provision of means whereby the repeater may be connected to, and 15 disconnected from, the talking circuit at the will of the operator.

Another object of the invention has reference to the provision of means whereby the operator may render the repeater operative or inoperative at will.

Another object of the invention is the provision of suitable equipment whereby an operator may control the amplification of the repeater.

A still further object of the invention is the provision of ringing equipment suitable for cooperation with a repeater, and more particularly the provision of means whereby in response to a ringing signal the repeater 30 is rendered inoperative so as not to be affected by ringing current.

These objects, together with other objects which will more fully appear in connection with the detailed description of the invention, are attained by arranging a repeater in connection with a cord circuit in such a manner that the operator by depressing a controlling key may disconnect the two ends of the cord circuit and connect a repeater organization therein, the operation of the key at the same time actuating means to connect a source of operating current to the repeater elements. The controlling key is also so arranged as to be adjustable to various 45 positions, in certain of which it may control an adjusting mechanism to vary the setting of the regulating rheostats in the output circuits of the repeater elements, thereby controlling the amplification of the repeater. 50 The means whereby the repeater is interpolated in the cord circuit is so arranged that if ringing current is received from the line, thereby actuating suitable ringing responsive mechanism, said means will hold the re-

peater connected to the cord circuit, but the 55 repeater will be rendered inoperative and unresponsive to ringing current.

The invention will be more fully understood from the following description when read in connection with the appended drawing, Figures 1 and 2 of which when placed side by side constitute a circuit diagram of a preferred embodiment of the invention.

Referring to the drawing, two lines L_1 and L_2 are shown terminating in twin jacks J_1 and J_2 , respectively. A cord circuit repeater arrangement is also shown terminating in twin plugs P_1 and P_2 , adapted to be inserted in jacks J_1 and J_2 . Associated with lines L_1 and L_2 are artificial balancing lines 70 or net works N_1 and N_2 , which are connected to the repeater organization when the twin plugs of the cord circuit are inserted in the jacks. Normally the upper halves of the two plugs P_1 and P_2 are connected over the 75 contacts of ringing keys 1 and 2 and splitting key 3, so that a direct connection is provided independent of the repeater, and, if so desired, the cord circuit may function as an ordinary toll cord circuit. Arrangements are provided, however, whereby the two ends of the cord circuit may be disconnected and the repeater apparatus interpolated in the circuit. For this purpose a controlling key arrangement is provided, 80 consisting of contacts K_1 , K_2 , K_3 and K_4 , said contacts being under the control of a movable member capable of assuming a plurality of positions. In the first position the contacts K_1 are closed. In the second position contacts K_1 and K_2 are closed. In position three contacts K_1 , K_2 and K_3 are closed, while in position four all of the contacts are closed. Upon operating contacts 85 K_1 , relays 4 and 5 are operated thereby disconnecting from the plugs that portion of the cord circuit comprising splitting key 3 and listening key 6, and connecting the repeater apparatus over the contacts of said relays to plugs P_1 and P_2 . The operation of 90 contacts K_1 also controls the energization of a relay 7, whereby a source of current is supplied to the repeater elements. The repeater organization comprises two repeater elements R_1 and R_2 , which are illustrated as of 100 the so-called mechanical type of repeater element, although it will be understood that any other well-known form of repeater ele-

95

105

ment may be used if desired. Repeater element R_1 comprises three windings 8, 9 and 10, as well as a variable resistance transmitting device 11. Windings 9 and 10 are in circuit with the source of current controlled by relay 7, and are differentially wound with respect to each other, the winding 9 being also arranged in parallel with respect to the variable resistance 11. Winding 8 is connected through induction coil 12 with the input bridge 13 of the repeater. Similarly, repeater element R_2 comprises windings 14, 15 and 16 as well as variable resistance transmitting element 17, said windings 14, 15 and 16 corresponding to and functioning in the same manner as windings 8, 9 and 10, respectively, of repeater element R_1 . A relay 20 is provided through the contacts of which the windings 8 and 14 of repeater elements R_1 and R_2 are normally short-circuited. Said relay is controlled through the contacts of the key K_1 and when energized operates to disconnect the short circuit about the windings 8 and 14 and connect said 25 windings directly to the secondaries of induction coils 12 and 18.

In the output circuit 21 of repeater R_2 , an output regulating arrangement is provided, said output regulating arrangement comprising resistance elements 22 and 23, the former being arranged to be connected in shunt across the output circuit 21, and the latter arranged to be connected in series with said circuit. Each resistance element, 22 and 23, is provided with a plurality of connecting points numbered 1, 2, 3, etc., said connecting points being controlled over the contacts of relays 24, 25 and 26 to variably determine the amount of resistance connected in shunt and in series with output circuit 21. In a similar manner, in the output circuit 27 of repeater element R_1 , an output regulating arrangement comprising resistances 28 and 29, is provided, resistance 28 being arranged to be connected in shunt of output circuit 27, and resistance 29 being arranged to be connected in series therewith. Said resistances 28 and 29, like resistances 22 and 23, are provided with a plurality of connecting points controlled over the contacts of relays 30, 31 and 32 to variably determine the amount of resistance in shunt and in series with the output circuit 27. Relays 24 and 30 are controlled by key contacts K_2 . Similarly, relays 25 and 31 are controlled by contacts K_3 , and relays 26 and 32 are controlled by contacts K_4 . When the controlling key member is moved to its first position so that contacts K_1 only are operated, 60 none of the output regulation controlling relays is actuated, and consequently the full resistances of elements 23 and 29 are connected in series with output circuits 21 and 27, respectively, while only the comparatively low resistances of the portions of po-

tentiometer elements 22 and 28 between points 1 and 4 are in shunt of said circuits. With this connection of the output regulating resistances the repeaters R_1 and R_2 are working under their conditions of lowest efficiency, and consequently a comparatively small degree of amplification results. If, however, the key controlling member is moved to its second position, thereby closing contact K_2 in addition to contacts K_1 , 70 relays 24 and 30 are actuated to complete the series and shunt connections to the second point of each potentiometer element, thereby decreasing the series resistance and increasing the shunt resistance. A greater degree of amplification therefore results. In a similar manner, by the actuation of contacts K_3 relays 25 and 31 are actuated to complete the connection from the third points of the potentiometer elements, thereby still further 80 decreasing the shunt resistance. Finally, if contacts K_4 are actuated, relays 26 and 32 will be operated to complete a direct connection for the output circuits 21 and 27 with no resistance in series therewith and with the 90 shunt elements of the potentiometer disconnected. With this arrangement of the circuits the repeater elements will be working at their greatest efficiency and the highest degree of amplification will be obtained. 95

Bridged across the conductors leading from the upper halves of plugs P_1 and P_2 are relays 33 and 34 responsive to ringing current. These relays jointly control a normally energized slow acting relay 41 which 100 in turn controls the circuit of a relay 66, whereby a lamp 35 may be caused to glow and a relay 36 be energized for a purpose hereinafter stated. The relays 33 and 34 are unresponsive to voice currents but will 105 respond to ringing currents or to intermittent currents of similar amplitude. The relay 41 being slow acting, however, does not respond to the intermittent actuation of relays 33 or 34 by intermittent currents, so 110 that a false signal of the lamp 35 does not result. Upon the actuation of either of these relays by ringing current, a signal lamp 35 is caused to glow and a relay 36 is actuated to open the circuit of relay 20 while maintaining relays 4 and 5 energized. This results in opening the secondary circuits of induction coils 12 and 18, and in short-circuiting the input windings 8 and 14 of the repeater elements R_1 and R_2 so that the repeater is not 120 actuated by ringing current. The same result may be obtained by throwing ringing key 1 or 2, as said keys are provided with contacts for energizing the relay 36. The listening key 6 is so arranged that when the operator throws this key in response to a ringing signal such as just described, the relays 4 and 5, which control the interpolation of the repeater in the cord circuit, are restored to normal and the repeater discon- 130

nected, the plugs P_1 and P_2 being again connected through the cord circuit proper so that the operator may listen in.

With this general description of the apparatus in mind, the invention may be fully understood from a description of the operation. Assuming that a call has come in over line L_1 , the operator in response to said call will insert the twin plug P_1 in twin jack J_1 , thereby completing a circuit over the sleeve contacts of the upper half of the plug and jack for relay 37. Upon the actuation of relay 37 a circuit is completed from ground over the lower front contact of said relay to point 38 and thence to point 39, from which point the circuit proceeds over the normal contact of ringing responsive relay 38, over conductor 40, normal contact of ringing responsive relay 34 and through the winding 20 of relay 41 to battery. The energization of relay 41 at this time produces no effect.

Having inserted the plug in the answering jack, the operator throws the listening key 6 to communicate over the calling line.

Having ascertained the desired connection, which it will be assumed is to be completed over line L_2 , the operator restores the listening key and inserts the plug P_2 in twin jack J_2 , thereby completing a circuit over the sleeve contacts of the upper halves of the plug and jack for relay 42. The operator now throws ringing key 2 and rings over the line L_2 . If it is desired to connect the repeater in circuit the operator actuates the

controlling key to one of its four positions, for instance, to its second position. This results in closing contact sets K_1 and K_2 . The closing of contact 43 of contact set K_1 completes a circuit from ground over the lower front contact of relay 37 to point 38 and over contact 43 and through the winding of relay 7 to battery. Relay 7, upon being energized, connects a battery 44 to the repeater elements R_1 and R_2 , thereby

rendering them operative. In case the ringing key has been restored to normal prior to the actuation of the controlling key, a circuit is completed over contact 45 of contact set K_1 , as follows: From ground over the lower front contact of relay 37 to point 38 and thence through point 39 to point 46, from whence the circuit continues over contact 47 of splitting key 3, contact 48 of said key, contact 49 of listening key

56, upper front contact of relay 42, over conductor 50, upper front contact of relay 37 to point 51, and thence over contact 45, conductor 52, winding of relay 20, normal contact of relay 36, to point 53, from which

point the circuit continues in parallel through windings of relays 4 and 5 to battery. The energization of relay 20 results in opening the short circuits existing around windings 8 and 14 of repeater elements R_1 and R_2 , and in the completion of a direct

connection over the front contacts of said relay between said windings 8 and 14 and the corresponding secondaries of induction coils 12 and 18, which are associated with the input bridges 13 and 19 of the repeater circuit. The energization of relays 4 and 5 results in the disconnection of the portion of the cord circuit including the splitting key 3 and listening key 6 from the plugs P_1 and P_2 , at the same time connecting said plugs over the front contacts of relays 4 and 5 to the repeater apparatus. The actuation of the controlling key to its second position results in closing contact K_2 , as well as contact set K_1 , thereby completing a circuit from ground over the lower front contact of relay 37 and over a path already traced to point 51, from which point the circuit proceeds over contact K_2 and through the windings of relays 24 and 30 to battery. The actuation of said relays results in the connection of the portion of output regulating element 22 between points 2 and 4 in shunt of output circuit 21 and the connection of the portion of output regulating element 23 between points 2 and 4 in series with said circuit. Output regulating elements 28 and 29 are similarly adjusted with respect to output circuit 27. Lines L_1 and L_2 are now connected through the repeater, which is adjusted to its second degree of amplification, and the conversation between the parties connected over lines L_1 and L_2 may proceed.

The operations previously described were based on the assumption that the ringing key 2 was restored prior to the actuation of the repeater controlling key. In case, however, the repeater controlling key had been operated prior to the restoration of the ringing key, the circuit previously traced through relay 20 and relays 4 and 5 in parallel would not have been completed, but the following circuit would have been completed instead; from ground over the lower front contact of relay 37 and over the path previously traced to point 51 and thence over contact 45 and over conductor 54 to point 55, thence over conductor 56 to point 57, over contact 58 of the ringing key 2 to point 59, over conductor 60 to point 61, and thence over conductor 62 and through the winding of relay 36 to battery. Relay 36 is energized over said circuit, thereby holding open the circuit already traced through relay 20 in series with relays 4 and 5 in parallel. A circuit is completed, however, over the front contact of relay 36 from ground to point 53, and thence in parallel through the windings of relays 4 and 5 to battery. Relays 4 and 5 are thereby actuated to connect the plugs P_1 and P_2 to the repeater, but relay 20 is not energized and consequently the input windings 8 and 14 of the repeater elements R_1 and R_2

are short-circuited. Upon restoring the ringing key 2 to normal the relay 36 will be de-energized, thereby completing the circuit previously traced through relay 20 in series with relays 4 and 5, so that relays 4 and 5 are maintained energized and relay 20 is operated to open the short circuits about the input windings of the repeater elements and to complete the connections between said windings and the induction coils 12 and 18. The connection is now completed between the lines L_1 and L_2 through the repeater, as already described, and the conversation may proceed.

15 If during the connection between lines L_1 and L_2 ringing current should be transmitted over one of the lines, say L_2 , to the repeater station, the ringing relay 34 bridged across the cord circuit would be energized.

20 This ringing relay is of high impedance to telephone currents and is not energized by such currents, but is so designed as to be readily responsive to the ringing currents which are of higher voltage and lower frequency. Upon being energized, said relay 34 at its contact opens the circuit previously traced for slow releasing relay 41, which thereupon is de-energized, closing at its back contact a circuit from ground, lower front

30 contact of relay 37, points 38, 39, 46, 63, 64 and 65, and thence over the back contact of relay 41 and through the winding of relay 66 to battery. Relay 66 upon being energized, at its lower front contact closes a circuit from ground, front contact of relay 37, points 38, 39, 46 and 63, thence over the front contact of relay 66 and through the winding of relay 67 to battery. Relay 67 upon being energized, at its left-hand front contact

40 closes a locking circuit from battery through the winding and over the front left-hand contact of said relay 67 to point 68 and thence over contact 69 of listening key 6, through points 64, 63, 46, 39, 38 and over the front contact of relay 37 to ground. Relay 67 at its right-hand front contact completes a circuit for the signal lamp 35, thereby indicating to the operator that a call has come in from one or the other of the lines interconnected through the repeater.

45 Returning again to relay 66, said relay at its upper front contact closes a circuit for relay 36 as follows:—from battery through the winding of relay 36, over conductor 62, point 61, conductor 60 to point 59 and thence over upper front contact of relay 66 to point 57, over conductor 56, through point 55, over conductor 54, contact 45, point 51, upper front contact of relay 37, conductor 50, upper front

50 contact of relay 42, contact 49 of listening key 6, contact 48 of splitting key 3, contact 47 of said key, points 46, 39, 38, and over the front contact of relay 37 to ground. Relay 36 upon being energized, at its front contact 55 closes a locking circuit for relays 4 and 5

and opens the circuit of relay 20 in the manner already described. Relay 20 upon being de-energized disconnects the input windings of the repeater elements from the input bridges of the repeater circuit and short-circuits said windings as already described.

55 The operator upon observing that the signal lamp 35 is glowing will now throw the listening key 6, thereby opening at contact

49 of said key the circuit just traced through the winding of relay 36, which circuit it will be remembered passed through the contact

49 of the listening key. Relay 36 is thereby de-energized, and again connects the windings of relays 4 and 5 to the winding of relay 20.

60 Relays 4, 5 and 20 are now de-energized since the circuit traced through relay 20 in series with relays 4 and 5 in parallel

65 passed through contact 49 of the listening key, which is now open. The de-energization of the relays 4 and 5 results in interconnection of the plugs P_1 and P_2 through that portion of the cord circuit including the splitting key 3 and the listening key 6, so

70 that the operator is now enabled to listen in and respond to the signal coming in over the line L_2 . The operation of the listening key also opened contact 69 thereof over which the locking circuit of relay 67 had been previously traced. Assuming that the ringing

75 signal has ceased so that the circuit of relay 41 is again completed over the back contact of ringing responsive relay 34, the circuit of relay 66 will now be opened at the lower contact of relay 41, so that relay 66 is de-energized.

80 Consequently both the initial energizing circuit and the locking circuit of relay 67 are opened and said relay is de-energized restoring the signal lamp 35 to normal.

85 The operator upon listening in by means of the listening key 6, and having ascertained that the call came from over the line L_2 , may, if desired, throw the splitting key 3 to the left, thereby disconnecting line L_1 from the cord circuit, and permitting the operator

90 to converse with the party on line L_2 independently of the party on the line L_1 . Suppose, now, with the listening key 6 thrown and the splitting key 3 thrown to the left, the ringing current should be transmitted over

95 the line L_1 to the repeater station, thereby actuating the ringing responsive relay 33.

100 The actuation of said relay would open the circuit previously traced through the relay 41, which relay upon being de-energized would close the circuit of relay 66, as already described.

105 Relay 66 in turn would close the initial energizing circuit of relay 67, which at its front right-hand contact would complete a circuit of the signal lamp 35, which lamp

110 would accordingly glow during the continuance of the ringing signal. The locking circuit previously traced for the relay 67 is now open at contact 69 of the listening key, and it is therefore necessary to provide another

- locking circuit for the relay 67. This locking circuit may be traced from battery through the winding and front left-hand contact of relay 67 to point 68, over conductor 70, contact 71 of splitting key 3, points 46, 39, 38 and over lower front contact of relay 37 to ground. The relay 67 will therefore be locked up so that lamp 35 will continue to glow until it attracts the attention 10 of the operator. The operator upon observing that the lamp 35 is glowing will know that the call came in from line L_1 , since the operator is already in communication with line L_2 . Accordingly the splitting key 3 may be restored to normal or thrown to the right. In either case contact 71 is opened, thereby breaking the locking circuit of the relay 67 and restoring the ringing signal to normal.
- 20 When it is desired to take down the connection between the lines L_1 and L_2 , the plugs P_1 and P_2 may be withdrawn, whereupon relays 37 and 42 will be de-energized. The de-energization of these relays breaks 25 the circuit already traced for relay 41. Furthermore, if the repeater had been connected in circuit, the circuit for relays 4, 5 and 20, which it will be remembered passed over the contacts of relays 37 and 42, will 30 now be open at the contacts of said relays 37 and 42 so that relays 4, 5 and 20 are de-energized, thereby disconnecting the repeater from the cord circuit. The circuit of relay 7 also passes over the lower front contacts of relays 37 and 42, and relay 7 is 35 therefore de-energized, disconnecting battery 44 from the repeater elements R_1 and R_2 . Likewise the circuit of output regulating relays 24 and 30 passes over the contacts 40 of relays 37 and 42, and consequently relays 24 and 30 are restored to normal. The apparatus is now in condition for setting up another connection.
- By means of the organization disclosed 45 the repeater will be under the full control of the operator, and it may be connected or disconnected, or its adjustment may be varied as circumstances may require. While the invention has been disclosed as embodied 50 in what is considered its most desirable form, it will be understood that the principle thereof may be embodied in many widely different organizations without departing from the spirit of the invention.
- 55 What is claimed is:
1. A repeater circuit including a repeater element comprising a variable resistance element and a magnetic means for controlling the same, a source of energy for said variable resistance element, relay means to control the connection and disconnection of said source with respect to said element at will, and a key for controlling said relay means.
  2. A repeater circuit including a repeater 60 element, means to energize said repeater element,

means whereby said energizing means may be connected to and disconnected from said repeater element at will, and a key for controlling said relay means.

3. A repeater circuit including a repeater 70 element, a regulating arrangement for controlling the amplification of the repeater element, a plurality of relays for controlling the adjustment of said regulating arrangement, and means for variably operating said 75 relays.

4. A repeater circuit including a repeater element, a regulating arrangement for controlling the amplification of the repeater element, a plurality of connections for said 80 regulating arrangement, relays for controlling said connections and manually controlled means for variably operating said relays.

5. A repeater circuit including a repeater 85 element, a plurality of relays, means controlled by said relays for determining the amplification of said repeater element, and means for variably operating said relays.

6. A repeater circuit including a repeater 90 element having an input and an output circuit, a net-work in the output circuit including series and shunt impedance elements, multiple connections whereby the series and shunt impedance of said net-work 95 may be varied, relays for controlling said multiple connections, and means for variably operating said relays.

7. A repeater circuit including a repeater element, a regulating arrangement for controlling the amplification of said repeater element, a plurality of connections for said regulating arrangement, a plurality of relays for controlling said connections, a repeater controlling key having a plurality of 100 positions, and means whose operation depends upon said key for variably energizing said relays.

8. A repeater circuit including a repeater element, a ringing responsive relay in said 110 repeater circuit, a relay controlled by said ringing responsive relay, and means controlled by the latter relay for rendering said repeater element inoperative.

9. A repeater circuit including a repeater 115 element, apparatus associated with said repeater circuit and unresponsive to telephonic currents or intermittent signaling currents, but responsive to continuous signaling currents, and means controlled by said apparatus for rendering said repeater element 120 inoperative.

10. A repeater circuit including a repeater element, apparatus associated with said repeater circuit and unresponsive to telephonic 125 currents or intermittent signaling currents, but responsive to continuous signaling currents, and means controlled by said apparatus for rendering said repeater element inoperative and for giving a signal.

11. In a signaling system, a plurality of transmission lines, a repeater for interconnecting said lines, signaling apparatus associated with said repeater and responsive to 5 ringing current transmitted over a line connected to said repeater, a listening key associated with said repeater and means responsive to the actuation of said listening key for restoring said signaling apparatus to 10 normal.

12. In a signaling system, a plurality of transmission lines, a cord circuit repeater for interconnecting said lines, a listening key and a splitting key associated with said 15 repeater whereby an operator may communicate with one line connected to the repeater and disconnect a second line connected therewith, signaling apparatus associated with said repeater and responsive to

ringing current, and means whereby when 20 the listening key is actuated and one line is disconnected from the repeater by said splitting key, said signaling apparatus is rendered responsive to signaling current transmitted over said last mentioned line. 25

13. In a signaling system, a plurality of transmission lines, a repeater for interconnecting said lines including mechanical repeater elements, input circuits for said repeater elements, and means whereby when 30 ringing current is transmitted over a line to which said repeater is connected, said repeater elements will be short-circuited and said input circuits opened.

In testimony whereof, I have signed my 35 name to this specification this ninth day of October, 1917.

JOHN F. TOOMEY.
